UNITED STATES PATENT OFFICE.

CLIFTON D. PETTIS, OF NEW YORK, N. Y.

PERMANENT CASTING MOLD.

Application filed November 28, 1924. Serial No. 752,547.

To all whom it may concern:

Be it known that I, CLIFTON D. PETTIS, a citizen of the United States, and a resident of the city of New York, county and State of New York, have invented certain new and useful Improvements in Permanent Casting Molds, of which the following is a specification.

The invention relates to casting iron and other high melting point metals in repetition or so-called "permanent molds". The invention seeks to provide an improved repetition mold of durable construction preferably formed of metal such as cast iron and made up of several parts or members movable to open and close the mold, and so constructed and arranged that ample provision is made for the expansion and contraction of the parts, for the dispersion of heat therefrom, and for the escape of air and gases from the mold cavity. A further object of the invention is to provide an improved repetition or permanent mold for the casting of brake shoes and to provide convenient means for supporting stiffening backs for the shoes within the mold cavity, and which are embedded or incorporated therein in the casting operation. With these and other objects in view, the invention consists in the features of improvement hereinafter set forth, illustrated in the preferred form in the accompanying drawings and more particularly pointed out in the appended claims.

In the drawings:

Fig. 1 is a side elevation of the improved mold.

Fig. 2 is a cross section on the lines 2—2 of Figs. 1 and 4.

Fig. 3 is a detail cross section on the lines 3—3 of Figs. 1 and 4.

Fig. 4 is a vertical longitudinal section taken on the line 4—4 of Fig. 5.

Fig. 5 is a view partially in plan and partially in section on the line 5—5 of Fig. 4.

Fig. 6 is an inverted plan view of one of the top sections or closure blocks, illustrating the manner of securing the stiffening back for the shoe to the top section.

Figs. 7 and 8 are detail sections illustrating the manner of supporting another form

of stiffening back for the shoe in the mold cavity.

The improved mold, as stated, is particularly designed for casting railway brake shoes, and for that purpose the parts or members of the mold are arranged to form an elongated mold cavity, substantially rectangular in cross section and so arranged that the brake shoe is cast in a horizontal position with its back, on which the center and end lugs are formed, uppermost.

The mold parts or members which form the bottom and side walls of the mold cavity are mounted upon a base 10 provided with upstanding lugs 11, and in which lugs horizontal pivot pins 12 and 13 are mounted. Side and end members 14 and 15 comprise hollow, box-like frames or receptacles formed of cast iron. The bottom walls of the frames or receptacles are provided with depending lugs 16 engaging the horizontal pivot pins 12 and 13, the end members being mounted on the pivot pins 13, and the side members both upon the same pin 12 which, in the preferred form shown, is in alignment with the vertical parting line or plane between the side members.

The frames of each of the side and end members are provided near their ends with pairs of outwardly projecting lugs 17 which engage circular cams or eccentrics 18, the latter being mounted on pivots having axes parallel to the axes of the respective members. Preferably, each pair of circular eccentrics or cams is formed integral with a transverse member 19 having a central handle 20, the unit comprising the connected pair of cams being mounted between the upper ends of lugs 21 on the base plate and supported thereon by pivot screws 22.

By operating these cams the side and end members of the molds may be readily and quickly moved to and from vertical closed positions with their inner walls or parting surfaces in engagement. The parts are so arranged that as the cams are moved to closed position, the cams 18 approach, but do not quite reach, dead center positions vertically above their pivots, so that the leverage of the cams on the mold members

increases as the latter approach closed position, and the parting surfaces are pressed into snug engagement to form joints which, while not necessarily air and gas tight, will prevent the escape of molten metal. This arrangement of the eccentrics or cams also serves to lock the mold members in closed position, making it unnecessary to employ additional clamps or the like. To prevent the accidental opening of the mold members during the casting operation, the end members 15 are preferably arranged to interlock with the side members to hold them in closed position. For this purpose, as most clearly shown in Fig. 5, the frames of the end members are provided at their edges with inwardly projecting flanges forming shoulders 23 which cooperate with shoulders 24 upon the side members and provide a safety guard or lock for preventing the opening of the side members until after the end members are opened. Preferably, the opening movements of the side and end members are limited respectively by pairs of lugs 25 and 26 formed upon the base 10 and cooperating with the lower lugs 17 on the members. Preferably, as shown, the lugs 26 which limit the movement of the side members are considerably higher than the lugs 25 which arrest the end members in open position, so that the opening movement of the side members is considerably less than that of the end members. The latter, of course, must be moved to a sufficient extent to clear the cooperating safety or locking shoulders 23 and 24, but the side members need only be opened sufficiently to move their inner cavity forming walls away from the finished casting.

40 The inner walls of the side and end members which form the walls of the mold cavity are divided into a number of sections so arranged as to permit the expansion and contraction of the sections as they are heated and cooled, and the escape of air and gases from the mold cavity. For this purpose the inner walls of the hollow side and end members are each formed of a series of hollow, open-backed metal blocks preferably of cast iron, each comprising an inner wall 27 and outwardly projecting top, bottom and side flanges 28. The blocks in the end frames 15 are superposed and the inner walls thereof are provided with recesses or seats 29 engaged by inwardly projecting flanges 30 on the side walls of the end members (see Fig. 5), so that the inner portions of the blocks project between these flanges and between similar flanges 31 formed upon the top and bottom walls of the end members. Retaining plates 32 form the outer side walls of the end members and are removably connected by screws to lugs 33 on the top, and bottom walls thereof, and these plates are provided with vertical ribs 34

which extend across and engage the top and bottom flanges of the blocks in the end members and hold the latter in position against the flanges 30 and with their inner vertical faces in alignment with the inner faces of the flanges 30 and 31. In the construction shown, stiffening ribs 35 extend between the ribs 34 on the cover plates 32. In this way the blocks are removably held in position within the end members, with the blocks for the most part out of contact with the walls thereof.

The blocks in the side members each extend nearly throughout the height thereof and in each side member are arranged side by side in a series extending longitudinally of the mold cavity and between walls or flanges 36 formed at the ends of the side frame or receptacle. The bottom wall 38 of each receptacle extends to the parting surface thereof and is provided with an upturned flange 39, while the top wall 40 is considerably narrower and has a downturned flange 41 at its inner edge. The flanges 39 and 41 engage seats 42 formed in the upper and lower edges of the side blocks or sections and retaining back plates 43 secured to the outer faces of the side members have longitudinal ribs 44 which extend across and engage the side flanges of the blocks and hold them snugly in engagement with the faces of the edge flanges 39 and 41. When thus held in position, portions of the side sections or blocks are flush with the abutting faces of the flanges 39 and form portions of the parting surfaces of the two side members. The remaining portions of the inner walls of the blocks form the bottom and side walls of the mold cavity, which, in the present construction conform respectively to the arched face and side walls of a brake shoe. It is noted that while these side blocks or sections are all substantially the same height, the inner abutting portions progressively diminish from the center towards the ends of the side sections in correspondence with the curvature of the face of the shoe. In the particular construction shown, the end walls or flanges 36 of the side frames are spaced somewhat from the ends of the frames and the end blocks of the series are provided with portions 45 which extend beyond these flanges to the vertical parting surfaces at the ends of the side members. Like the retaining or back plates of the end sections, the plates 43 are connected by screws to lugs 33 formed on the outer edge portions of the side frames, and stiffening flanges extend between the flanges 44.

The retainer plates 32 and 43, and preferably also the side walls of the end members and the bottom walls of the side members, are provided with openings 46 for the free circulation of air through the members and about the blocks or sections and there-

by aid in preventing the overheating of the blocks. Furthermore, the construction of the blocks with their inner walls 27 of substantially uniform thickness and their outwardly projecting, stiffening flanges 28, which are preferably relatively thinner, is such that while the blocks are quite stiff and rigid, heat is readily dispersed therefrom and they are not subject to excessive strains, due to unequal heating and cooling of different portions thereof. It is particularly noted that the inner walls, which, as stated, are of substantially uniform thickness, should be sufficiently thin to readily dissipate the heat to which they are subjected and avoid the development of strains due to unequal heating and cooling. On the other hand, these walls should be sufficiently thick (preferably about $\frac{5}{8}$ of an inch in the present construction, where it is designed to cast a railway brake shoe) to avoid distortion or warping.

It is also noted that the dividing of the inner wall of each of the mold members into separate blocks or sections avoids the transmission of strains due to the heating and cooling throughout the extent of these walls, as would be the case if they were formed of a single piece.

Ample provision is also made for the expansion and contraction of the individual blocks or sections. For this purpose, the blocks are of such dimensions that they do not snugly fit between the edges of the flanges at the inner edges of the side and end frames or receptacles. Thus, the length of one of the series of blocks in each side member is slightly less than the length of the mold cavity. In the present construction, that is designed to cast a brake shoe of the standard size, the combined width or length of the series of blocks in each side frame is preferably about $\frac{1}{16}$ of an inch less than the length of the mold cavity, so that the series of blocks (seven in number in the construction shown), fit loosely between the end walls or flanges 36 of the side frames. There is also a clearance preferably of about $\frac{1}{64}$ of an inch between the shoulder seats of each block and the edges of the flanges 39 and 41 between which they fit and there is a similar slight clearance between the blocks in the end frames and the edges of the flanges 30 and 31. It is also noted that while the blocks are snugly held in position between the ribs or retaining back plates and the faces of the inner edge flanges, they are otherwise for the most part held out of contact with the walls of the receptacles or frames. This arrangement aids in permitting the expansion and contraction and the limited adjustment of the individual blocks or sections without warping or distortion of the parts of the mold. Not only is the construction such that dis-

tortion and injury of the parts of the mold, due to heating and cooling are avoided, but the sectionalizing of the mold cavity permits the ready escape of air and gases therefrom. A modified form of block or section for the side members is shown in Fig. 3. In this form, the outwardly projecting flange at the bottom of the block is omitted so that it can be somewhat more readily cooled by the air circulating around it.

The blocks or sections in the side or end members are, as stated, firmly held against inward or outward movement between the ribs of the retainer back plates and the faces of the edge flanges, so that when brought to closed position the blocks will engage sufficiently snugly at the vertical parting surfaces between the side members and between the latter and the end members to prevent the escape of molten metal from the mold cavity.

When closed, the side and end members form a horizontally elongated, open-topped mold cavity conforming in the present instance to the face, side and end walls of a brake shoe, and it is noted that these members form in effect a multi-part drag. In the present construction, the use of a member like the ordinary cope for forming the top wall of the mold cavity, is avoided. Instead, a number of small, easily handled separate sections adapted to be detachably supported on the drag members, are used. In the mold shown in Figs. 1 to 5 inclusive, the closure for forming the top of the mold cavity comprises two end sections and an intermediate central section, all preferably formed of cast iron. The central section is preferably formed of two end blocks 47 and two intermediate blocks 48. These blocks are arranged side by side and fastened together by bolts 49. The end sections 50 and 51 are entirely separate from the center section and preferably one of these sections, for example the section 50, is formed of two like parts having vertical parting faces extending longitudinally of the mold, these faces being recessed to form a pouring gate 50'. All of the top or closure sections are provided on their outer side walls with projections or ribs 52 which preferably form continuous shoulders having flat, horizontal lower faces that engage the inner edge portions of the top walls of the side and end members. Each of the top sections also comprises a portion which projects downwardly below the shoulders or ribs 52 and fits between the upper portions of the inner vertical faces of the drag members when the latter are closed. These depending portions, or at least the extreme lower parts thereof are of substantially the same width as the mold cavity and extend below the upper edges of the blocks or sections in the side members. The lower surfaces of the closure

125

130

blocks or sections conform to the arched top of the mold cavity, but it is noted that the parting surfaces between the top closure sections and the other members of the mold are flat.

The lower faces of the end blocks or sections 50 and 51 are provided with suitable recesses 53 which form the end lugs on the back of the brake shoe, and the blocks 48 of the central sections have recesses for forming the center attaching lug. Preferably, also, these blocks are recessed to receive the ends of a sand core 54 for forming the opening in the attaching lug and also, in the particular form shown, these blocks are shaped to receive a reinforcing steel lug 55. This U-shaped steel lug as usual is arranged to engage a strengthening steel back 56 having longitudinal slots 57 therein. To hold the back in place the meeting faces of the blocks 48 and 47 of the center section are provided with thin grooves or slits that receive two thin, flat, metal attaching clips 58. These clips are adapted to be passed through the grooves in the center section and the slots 57 of the back 56, and have offset lower ends 59 for engaging the inner face of the back. The upper ends of the clips are adapted to be bent into engagement with the upper face of the center closure section and so clamp the back snugly against its lower face. The clips frictionally fit the grooves of the center closure section and snugly fit the inner ends of the openings 57 of the back so that the latter is accurately positioned in the mold cavity and snugly held against the top wall thereof. It is also noted that the top or closure sections fitting as they do within the upper portions of the movable side and end members, are accurately positioned or centered when the members are closed.

As an aid in positioning the closure blocks and also to securely hold them against displacement, the upper walls of the side members are provided with lugs 60 adapted to overlie the ribs or shoulders 52 formed on the closure sections. Preferably the meeting faces of the shoulders and lugs are inclined as shown, so that they may be brought into snug contact when the side members are closed. When the side members are in their open position as determined by the stop lugs 25, the lugs 60 are of course moved away from the shoulders 52 so that the closure sections may be readily placed in or removed from position, but in this extreme open position, the shoulders 52 cannot clear the upper inner edges of the side members and hence cannot be dropped or fall into the mold cavity. Therefore, when the mold members are open the top or closure sections can be readily and quickly placed in position and are automatically centered and locked in proper position when the side members are moved and locked in closed

position by their operating cams 18. Then, when the end sections are similarly moved to and locked in closed position by their operating cams, the shoulders 23 thereof overlie the shoulders 24 of the side sections, as previously noted, and act as a safety lock to prevent the displacement of the other mold parts until the end members are again open.

To prevent the escape of molten metal from between the parts of the end section 50, the meeting faces thereof are provided on opposite sides of the pouring gate with vertical matching ribs and grooves 61. By dividing the center section into separate blocks, the grooves for the attaching clips 58 and the recesses for forming the center lug and for receiving the core and center lug reinforcement can be readily formed in the different blocks before they are secured together. It is also noted that the grooves which receive the attaching clips intersect the recesses which receive the ends of the core 54, and these grooves thus form vents for the core. Also, to permit the escape of air and gases from the upper portion of the recess that forms the center lug, the meeting faces of the blocks 48 are provided with venting grooves 62. These blocks also, preferably, have projecting eyes 63 by which the center section and finished shoe can be removed as soon as the mold is opened. By forming the top closure of small, separate sections, they can be readily handled and placed in and removed from position. Furthermore, the dimensions of these sections are such that narrow venting spaces of preferably about 1/100 of an inch, are formed between them and permit the escape of air and gases from the mold cavity, but do not allow the passage of molten metal. Thus, in the present construction for casting a standard brake shoe, the combined length of the three closure sections is $\frac{1}{2}$ of an inch less than the length of the mold cavity. Preferably also the lower portions of the closure blocks or sections that fit between the inner vertical faces of the side members when the latter are closed, are about $\frac{1}{64}$ of an inch less in width than the mold cavity. The arrangement permits the expansion and contraction and limited adjustment of the closure blocks and also provides for free venting of the mold cavity. At the same time, the closure sections can be easily and quickly placed in and removed from position, are accurately centered between the side and end members when the latter are closed and the joints at the parting surfaces, while permitting venting, are sufficiently snug to be metal tight.

In the present construction, the recess for forming the center lug in the center closure section, has a width at its lower portion the same as that of the shoe and for this reason the center section is somewhat wider than

the end sections 51 and 52, and the edge flanges 41 at the upper portions of the side members are correspondingly recessed. If desired to lighten the closure blocks or sections and effect a more rapid dissemination of heat therefrom, they may be made hollow or provided with depressions 64 in their outer faces. It is also noted that the end blocks 50 and 51 are of the same size so that 5 they are interchangeable and preferably, in practice, the position of these blocks is changed at each operation so that the different portions of the mold are subjected at successive pourings to the high heat of molten 10 metal entering the mold through the pouring gate.

At each operation the faces of the mold sections or blocks are cleaned and preferably provided with a suitable protective coating. 20 These operations are facilitated since, in open position, the upwardly and outwardly inclined mold faces are exposed. Then after attaching the back to the center closure section, it, together with the end sections, are 25 placed upon the side members, the latter and the end members closed in the order named and the molten metal poured into the mold cavity. Preferably, as soon as the molten metal has set but before it has contracted to 30 any extent, first the end and then at least one of the side members are opened so that the walls thereof are swung out of contact with the casting, it being noted that the arrangement is such that in this opening movement of the side and end members there is 35 no scraping or rubbing between the faces of the mold cavity and of the casting. When the members are thus opened, the top closure sections and the completed casting are 40 removed by gripping the center closure section with tongs or the like. Then, before there can be any locking between the end lugs of the shoe and the closure section due to the cooling and contraction of the casting, 45 the end closure sections 50 and 51 are removed. But even if this is not done, the bringing together of these end lugs by the contraction of the casting will tip or tilt the end sections 50 and 51 so that there will be 50 no strains or rupture developed either in the casting or in the closure sections, because the latter are free to move relatively to one another. Then when the casting has contracted sufficiently to free the center lug of 55 the shoe from the intermediate closure section, it can be easily disconnected therefrom by bending the upper ends of the clips 58 so that they can be withdrawn from the grooves in the center closure section. 60 The improved mold may also be employed for casting a brake shoe having a substantially continuous strengthening steel back or shell, as shown in Figs. 7 and 8. This particular steel back or shell 65 shown in these figures is provided with a down-

turned reticulated edge flange 66, the lower reticulated portion of which is inwardly offset so that it is embedded in the shoe and spaced to some extent from the side faces thereof. The back is also provided with a 70 center lug 67, with an opening 68 to permit the passage of molten metal therethrough from the pouring gate, and with openings 69 to permit the passage of metal into the end lug cavities 53 of the end closure blocks 75 or sections 50 and 51. In casting a shoe of this type, the center closure section is omitted. Instead, the shell, which forms the top wall of the mold cavity, is held in proper position preferably by means of one 80 or more transverse members or bars 70 adapted to rest upon the upper edges of the side members and are provided with laterally projecting lugs 71 adapted to engage the center lug on the back of the shell. 85 Preferably, the upper faces of these lugs are cam or wedge-shaped so that, as they are forced into the upper portion of the center lug, they will draw the shell snugly up into engagement with the lower faces of the 90 end blocks or sections 50 and 51 and form metal tight joints therewith. For convenience, if desired, the members 70 may be provided with arms 72 connected by a pivot pin 73. To provide good metal tight joints 95 between the steel back or shell and the side members of the mold, and also to aid in holding the shell in place, the latter is made of such width that it is gripped between the side members when the latter are closed. 100 Thus for a standard passenger car brake shoe, the shell is preferably made $\frac{1}{64}$ of an inch wider than the mold cavity, and it will yield slightly when the side members 105 are brought to closed position.

Fig. 8 illustrates the manner of positioning a steel back or shell and an insert in the mold comprising a number of superposed layers of expanded metal which are cast into the face portion of the shoe. These layers are bound together at spaced intervals by wires 76, the upper portions of which are twisted together and provided with laterally projecting portions 77, the ends 78 of which are arranged to fit within the downturned edge flanges of the steel shell or back. In this way the insert and steel shell may be connected together and placed as a unit within the mold and the connected parts will serve to properly position each other during the casting operation. That is to say, the insert connecting wires will assist the positioning of the shell in the mold cavity and the shell, which is of course prevented from rising by the end closure blocks, will in turn hold the insert in proper position in the lower portion of the mold cavity. When the mold is used as illustrated in Figs. 7 and 8, the joints 110 between the back or shell and the mold 115 120 125 130

members are sufficiently tight to prevent the passage of molten metal, but they are not and cannot well be made air and gas tight, so that ample provision is made for the 5 venting of the mold.

In the improved mold, the walls of the cavity or matrix are sectionalized and the metal sections so arranged and supported that each can expand independently of the 10 others, thus localizing strains due to heating and cooling. Furthermore, excessive heating and distortion of the metal parts of the mold is prevented by the provision for the circulation of air through the hollow frames 15 or receptacles and about the blocks, by the formation of the mold into separable parts or members, so that the casting can be readily and quickly removed from contact 20 with the walls of the mold cavity, as soon as it is set, and particularly by the described construction of the hollow, box-like frames and hollow mold sections or blocks, the walls of which are quite thin and present 25 large surface area for the rapid radiation of heat. In this connection it is noted, that, while the individual blocks are quite rigid, the walls of the frames or receptacles in the particular construction described are, for the most part, preferably only $\frac{1}{4}$ of an 30 inch thick so that they are slightly yielding or flexible and will absorb strains due to the expansion of the parts of the mold without permanent distortion or rupture. Also, as an aid in avoiding distortion, the 35 edge flanges of the frames, which position the blocks and are preferably thickened, are provided at intervals with transverse slits 79 as described most clearly in Fig. 5.

As previously pointed out, clearance is 40 provided between the blocks that form the sectionalized walls of the mold cavity and between the blocks and the edges of the frame flanges between which they loosely fit, and an attempt has been made to indicate 45 such clearance spaces in the drawing. But it should be understood that such spaces are much narrower than is indicated or can be indicated in small scale drawings, and, for the most part, do not exceed $1/100$ of an 50 inch. Indeed the metal blocks in the frame members and the top closure blocks can be placed in position side by side with their adjacent walls loosely contacting. Nevertheless, because of the clearance allowed and 55 the limited freedom of adjustment permitted, the joints between the blocks or sections and between the mold parts, while sufficiently tight to prevent the escape of molten metal and the formation of fins that would 60 interfere, with the ready removal of the castings, permit the expansion of the parts and the free venting of the gases from the mold cavity. The attainment of these advantages is affected or aided by forming the 65 receptacles and blocks of cast iron, by

clamping the blocks so that they cannot move laterally to and from the vertical parting surfaces of the pivoted side and end members of the mold, and by the construction and arrangement of the metal closure 70 blocks or sections. In this connection it is noted that the closure blocks fit between the upper portions of the inner vertical walls of the side and end members and are provided with shoulders that rest on the upper 75 edges of the mold members, so that good joints are formed between the flat vertical and horizontal faces of these parts, when the mold is closed. It is also noted that the depending portions of the closure blocks, in the form shown in Figs. 1 to 5 inclusive, and the edges of the back or shell in the forms shown in Figs. 6 and 7, cover the joints between the upper ends of the blocks 80 in the side members and the upper edge 85 flange members 41, so that the formation of fins between these parts is prevented. The formation of good metal tight joints between the several parts of the mold is also aided by the construction and arrangement 90 of the opening and closing cams 18 and the interlocking shoulders and lugs 52 and 60 of the closure blocks and side members, all of which serve to press the mold parts into 95 engagement. Notwithstanding the fact that the mold, as stated, is made of a number of parts, so that the casting as soon as it is set can be readily disengaged from contact therewith, provision is made whereby the parts can be quickly opened and closed and 100 interlocked in closed position without the aid of supplemental clamps, screws or the like.

While the employment of permanent molds for the casting of brake shoes has been heretofore many times attempted, it has been found that because such castings are thick and heavy and do not readily and quickly cool, that it is extremely difficult to do so, and at the present time practically all brake shoes are made in sand molds. However, for the reasons above noted, the present improved mold is well adapted to the successful and rapid operation of the casting of brake shoes. It is particularly 105 noted that the use of the mold for casting brake shoes is facilitated by the arrangement of the pivoted side and end members forming a closed and open-topped cavity 110 that conforms to the face, side and end walls of the brake shoe, and a closure detachably mounted on these members fitting 115 within the same and forming the back of the shoe and center and end lugs thereof. As already noted, by forming the closure of 120 sections that are entirely separate and detachable from one another and from the other members of the mold, they can be readily disengaged from the irregular back 125 face of the shoe. The closure also, as 130

pointed out, affords convenient means for quickly and accurately positioning stiffening backs and inserts in the cast brake shoe.

While many of the details set forth are important and are covered by the appended claims, changes may be made without departure from the essentials of the invention as defined in the claims.

I claim as my invention:

1. In a permanent mold for castings, mold members movable to and from closed position and each comprising a box-like metal frame or receptacle and a series of hollow metal blocks arranged side by side therein and each comprising side flanges and an inner wall forming a portion of the mold cavity and a portion of the parting surface of the mold member, said frame having means engaging a wall of said blocks, and a removable plate provided with means engaging the flanges of the blocks to removably hold the latter in position, substantially as described.

2. In a permanent mold, mold members movable to and from closed position and each comprising a frame and a series of hollow backed metal blocks forming at least part of the mold cavity, said frame having openings through its walls for the free circulation of new air about the blocks, substantially as described.

3. In a permanent mold for iron and like castings, mold members movable to and from closed position and each comprising a box-like metal frame or receptacle and a series of hollow metal blocks arranged side by side within said frame and each comprising side flanges and an inner wall forming a portion of the mold cavity and a portion of the parting surface of the mold member, said frame having inner edge flanges engaging the inner walls of said blocks and a removable back plate provided with ribs engaging the side flanges of the blocks to removably hold the latter in position, substantially as described.

4. In a permanent mold for iron and like castings, mold members movable to and from closed position and each comprising a box-like metal frame or receptacle and a series of hollow metal blocks arranged side by side within said frame and each comprising side flanges and an inner wall forming a portion of the mold cavity and a portion of the parting surface of the mold member, said blocks having recessed seats at the opposite edges of their inner walls and said frame having inner edge flanges engaging said seats and removable back plates provided with ribs engaging the side flanges of said blocks, substantially as described.

5. In a permanent mold for iron and like castings, mold members movable to and from closed position and each comprising

a box-like metal frame or receptacle and a series of hollow metal blocks arranged side by side within said frame and each comprising side flanges and an inner wall forming a portion of the mold cavity and a portion of the parting surface of the mold member, said blocks having recessed seats at their opposite edges of their inner walls, said frame having inner edge flanges engaging said seats and removable back plates provided with ribs engaging the side flanges of said blocks, and said frame having openings for the circulation of air about the blocks, the parts being arranged to permit the expansion of the block and the escape of gases between the same, substantially as described.

6. In a permanent mold for iron and like castings, a base, a plurality of mold members pivoted on the base to move to and from closed position and comprising metal frames and a series of hollow, open-backed, metal blocks arranged side by side within each of said frames and adapted to abut in the closed position of the mold members to form the mold cavity, said frames having openings in their walls to permit the circulation of air about the blocks and having means for removably holding the blocks in position therein and in a manner permitting the expansion of the blocks and the escape of gases between the same, substantially as described.

7. In a permanent mold, mold members movable to and from closed position and each comprising a frame and a series of hollow metal blocks forming at least part of the mold cavity, said frame having openings through its walls in different horizontal planes for the free circulation of new air about the blocks, substantially as described.

8. In a permanent mold for casting brake shoes and the like, a pair of movable side members each comprising a metal frame and a series of hollow metal blocks arranged side by side within the frame in a series extending longitudinally thereof and of the mold cavity, said blocks having inner walls of substantially uniform thickness forming the parting surfaces of said side members and the bottom and sides of the mold cavity and each block having relatively thinner side walls, and seats at the upper and lower edges of its inner walls, and said frames having flanges at their upper and lower inner edges engaging the seats of said blocks and removable back plates provided with ribs engaging the side flanges of the blocks, substantially as described.

9. In a permanent mold for casting brake shoes and the like, a base, a plurality of mold members movably mounted on said base and comprising box-like metal frames having inner edge flanges and removable back plates and a series of hollow

- metal blocks arranged side by side within each of said frames and having inner walls of substantially uniform thickness and outwardly projecting side flanges, the inner walls of the blocks being arranged to abut in the closed position of the mold members and having portions forming the bottom, side and end walls of an elongated mold cavity, said walls having shoulder seats at their upper and lower edges engaging the inner edge flanges of said frames and said back plates having ribs extending across and engaging the outer edges of the side flanges of the blocks, said frames having openings in their walls for the circulation of air about the blocks and the dimensions of the frames and blocks permitting the expansion and limited adjustment of the blocks and the escape of gases between the same, substantially as described.
10. A permanent mold for casting brake shoes having a horizontal, elongated mold cavity substantially rectangular in cross section and comprising a base, side members pivotally mounted on said base, a longitudinal series of metal sections removably mounted in each of said members and constituting the inner walls thereof, each such wall having portions of substantially uniform thickness forming part of the bottom and one of the sides of the mold cavity, separate metal members forming the ends of the cavity and a metal closure adapted to be detachably mounted on said side and end members and forming the top of the mold cavity, substantially as described.
11. In a permanent mold, mold members movable to and from closed position and each comprising a frame and a series of flanged metal blocks, said frame having means loosely engaging the flanges of said blocks for removably holding the same in position in a manner permitting the expansion of the blocks, substantially as described.
12. In a permanent mold, mold members movable to and from closed position and each comprising a frame and a series of hollow metal blocks, said frame having means loosely engaging said blocks for removably holding the same in position in a manner permitting the expansion of the blocks while maintaining a constant overall mold cavity length, substantially as described.
13. In a permanent mold, a pair of movable side members each comprising a frame and a series of transversely divided hollow metal blocks loosely arranged side by side within the frame in a series extending longitudinally thereof and of the mold cavity, substantially as described.
14. In a permanent mold, a pair of movable side members each comprising a frame and a series of transversely divided hollow metal blocks arranged side by side within the frame in a series extending longitudi-

nally thereof and of the mold cavity, substantially as described.

15. In a permanent mold, mold members movable to and from closed position, each mold member comprising a frame and a series of hollow metal blocks forming a common cavity and loosely carried thereby for floating movement under expansion, substantially as described.

16. In a permanent mold, mold members movable to and from closed position, each member comprising a frame and a series of hollow metal blocks carried thereby, said frame being constructed to permit movement of the blocks relatively to each other and to the frame, substantially as described.

17. As an article of manufacture, an openable casting mold having at least a portion of its molding surface formed by a plurality of adjacent relatively movable hollow metal blocks, and means loosely supporting said blocks to permit expansion or contraction thereof without changing the over-all dimensions of the molding surface, substantially as described.

18. As an article of manufacture, an openable casting mold having at least a portion of its molding surface formed of a plurality of adjacent relatively movable hollow metal blocks, and means loosely supporting said blocks to permit relative floating movement thereof, substantially as described.

19. As an article of manufacture, a casting mold having at least a portion of its molding surface formed of a plurality of adjacent relatively movable hollow metal blocks, and means loosely supporting said blocks, said means providing passages behind the blocks for the free circulation of air against the backs thereof and having openings to the atmosphere providing free circulation of air to said passages, substantially as described.

20. As an article of manufacture, a mold having a molding cavity, and a closure for said cavity, said closure comprising an interchangeable pouring gate section and a filler section, substantially as described.

21. As an article of manufacture, a mold having a molding cavity, and a closure for said cavity, said closure having interchangeable end sections comprising, respectively, a pouring gate section and a filler section, substantially as described.

22. As an article of manufacture, a mold having a molding cavity formed by a plurality of relatively movable sections, and a closure for said cavity, said closure comprising an interchangeable pouring gate section and filler section, substantially as described.

23. The method of forming castings, comprising pouring successive castings from opposite ends of the mold, substantially as described.

24. The method of forming castings, comprising reversing the position of the pouring gate after at least certain of successive casting operations to thereby deliver the molten metal initially to different portions of the mold cavity, substantially as described.
25. In the method of repetition casting,
- the step consisting of maintaining a more nearly uniform average mold temperature, comprising initially delivering the molten metal to different portions of the mold for successive casting operations in the same mold, substantially as described. 10
